UNITED STATES PATENT OFFICE

ISAAC HARDY PARSONS, OF KIBWORTH HARCOURT, NEAR LEICESTER, ENGLAND.

ELECTRICAL COUPLING.

1,014,718.

Specification of Letters Patent.

Patented Jan. 16, 1912.

Application filed March 8, 1910. Serial No. 547,956.

To all whom it may concern:

Be it known that I, ISAAC HARDY PARSONS, a subject of the King of Great Britain, and a resident of The Croft, Kibworth Harcourt, near Leicester, England, have invented certain new and useful Improvements in Electrical Couplings, of which the following is a specification.

My invention relates to improvements in electrical connectors or coupling members; and more particularly to connectors of the "snap-on" type, such as those in which metal plates or wires spring apart and snap over the projecting head of a stud or knob to make electrical connection therewith.

It has for its object to so construct the said connector that the springiness of the metal of the same will be assisted by some suitable elastic insulating material to cause the stud or the like to be hugged tightly should the metal members be overstrained, or for any cause fail to grip the said stud tightly. In case the metal members are without spring of any kind, the elasticity of the insulating material will insure a close electrical contact.

It has for its further object to completely embed the said contact members, as well as the connecting wires, in the said elastic insulating material leaving only openings, preferably blind, at each terminal to receive the stud; also, to so construct the same that a water-tight, high insulation connection may be made with said stud.

The nature of my invention will be best understood in connection with the accompanying drawings, in which—

Figure 1 is a longitudinal section of a complete electric connector; Fig. 1^a an elevation of the stud; and Fig. 1^b a plan of said stud. Fig. 2 is a vertical section of a connector in engagement with its stud. Fig. 3 is a vertical section of a connector with duplicate conductors and contact members; Fig. 3^a the corresponding stud therefor; and Fig. 3^b a view of the underside of the connector. Fig. 4 is a horizontal section of a modified form of contact member. Figs. 5 and 5^a are respectively vertical sections of the said modified connector and the corresponding stud therefor. Fig. 6 is a horizontal section of a connector similar to that shown in Fig. 4, but provided with duplicate contact members. Figs. 7 and 7^a are vertical sections of a coupling similar to that

shown in Figs. 4, 5, and 5^a, but with the members reversed. Fig. 8 is a horizontal section of a connector similar to that shown in Fig. 6, but in which the connection is effected by applying a circular motion to one of the coupling members. Fig. 9 is an elevation of a coupling in position, but disconnected from the corresponding studs. Figs. 10 and 10^a are longitudinal sections of connectors of ball pattern, and in which both of the contact members are embedded in an elastic insulating material. Figs. 11 and 12 are vertical sections illustrating couplings in which conductors of varying lengths may be attached by those employing the same to meet special requirements. Figs. 13 and 14 are vertical sections of a coupling provided with a long stud.

Similar characters of reference designate corresponding parts throughout the several views.

Referring now to Figs. 1, 1^a, 1^b, I employ two D-shaped metal pieces D, D¹ as the contact members, said members being preferably formed of wires bent into the form of a D, and provided with an indentation D² in the vertical line of the D. These pieces are disposed so as to form a circle, and are embedded in india rubber A, or equivalent insulating material, forming a disk-shaped pad or cushion E. Opposite to the indentations D², a circular opening C is made in one side of the cushion, said openings being adapted to receive the metal stud B on which the contact members are adapted to snap, upon the latter's being forced over the same by the pressure, of for example, the user's thumb on the top of the cushion E. The two pairs of contact members D, D¹ are connected by means of a suitable conductor or conductors A², and preferably by a non-stretching cord A⁴. The conductor A², as well as cord A⁴, is likewise covered with india rubber which is vulcanized to the cushions E so as to form one piece therewith. The stud B is mounted in an insulating base G, the face of which may be fluted or flanged as shown, so that as the cushion E impinges thereon it will establish with the same a water-tight, high insulating connection, the contact members producing a back pressure under the head of the stud.

Fig. 2 shows the corresponding parts of the coupling in position, the cushion E fitting upon the insulating base G which is

adapted to be fixed to some support (not shown) as by means of suitable screws G^5 . An insulated conducting wire H is soldered at H^2 to the stud B , and an insulating filling G^6 is provided in the sink G^4 .

Figs. 3, 3^a, 3^b, show the contact pieces D , D^1 separated to form duplicate connectors. These contact members are securely anchored within the india rubber A , 10 and are connected respectively to the conductors A^3 and A^5 . Through separate openings C , C^1 contact may be made with the twin contact studs B , B^1 .

Figs. 4, 5, and 5^a illustrate a modified 15 form, the contact piece being provided with an opening C^3 and slot D^6 and the piece itself is provided against unduly moving within the rubber by suitable anchoring horns D^6 , D^7 . The conductor A^2 is soldered 20 at A^6 to this piece. In this pattern connection is established by inserting the stud B of the corresponding member into the opening C^3 and sliding the same to its central position in the slot D^6 , electrical connection 25 being maintained by the back pressure of the rubber which is compressed somewhat during the action of connecting the two members.

In Fig. 6 a duplicate connector of the 30 type illustrated in Fig. 4, is shown. Duplicate contact pieces D , D^1 are provided and duplicate conductors A^3 and A^5 are soldered thereto at A^6 and A^9 .

Figs. 7 and 7^a illustrate a coupling of the 35 pattern shown in Figs. 4, 5 and 5^a, but with the members of the coupling reversed. In this latter form a stud B is embedded in the detachable rubber cushion E instead of being fixed in the base G , and the piece D is 40 fixed in the insulating base G .

A coupling of construction similar to that illustrated and described with references to Fig. 6, is shown in Fig. 8, connection, however, being made by inserting the studs of 45 the corresponding member (not shown) into the holes D^3 and D^4 and then applying a circular motion to the connector.

A useful application of the invention is 50 in those instances where it is desired to make electrical connection to fixed objects by means of a flexible and movable connection as for example, between a motor-car lantern and the dash-board of the car. In such instances, two insulated studs T , T^1 , 55 (Fig. 9) are provided, one being fixed to the lamp holder of the lantern and one to the dash-board of the car. A coupling member may be attached to these studs by simply pressing upon the cushion E of the same.

50 Referring to Figs. 10 and 10^a, a modified form of connector is shown. The contact members in this case are in the form of a metallic loop D and a hook B both of which are embedded and anchored in elastic insulating material A . Electrical connection is

established between the two members by pressing them together with a lateral movement so as to cause the hook B to engage the loop D . The depressions C and C^1 are formed to facilitate this movement. As the hook B engages the loop D , electrical contact is made, the elasticity of the rubber in contact tending to force the two members of the coupling apart, and also to maintain the necessary pressure between the contact 75 surfaces.

In Fig. 11 the contact piece D is shown cup-shaped and is provided with anchoring holes D^7 . The conductor A^2 in view of varying requirements as to the length may 80 be placed in the desired position by the user and soldered to the contact piece D as at the point H^2 . The stud B is in this embodiment shown split and the hole D^8 of piece D is adapted to snap over same, the connection 85 being assisted by the back pressure of the rubber cushion A bearing against the flange G^1 , thereby holding the member D in contact with head of the stud D . A water-tight joint is established at G^1 .

90 Fig. 12 shows a similar construction, the hole in the plate D , however, being located eccentrically, while the stud B is fixed centrally.

Figs. 13 and 14 illustrate a form of coupling such as shown and described in connection with the coupling set forth in Figs. 7 and 7^a. The stud B in this form, however, is longer and projects well into its corresponding member. The said stud projects 100 also upward through the cushion A , and is covered with the insulating material to form a handle A^7 . The conductor A^2 is soldered to the stud B at the point H^2 , and the conductor H to a metallic cross-pin D of triangular cross-section. Electrical connection is established between the members B and D by pushing the stud B into the member G until its head engages the under side of the metallic cross-pin D . A water-tight connection is also established at G^1 . Many useful applications of this connector will readily suggest themselves, and it is obvious that the cushions, the contact pieces, etc., may be made in many forms and designs without departing from the spirit of my invention. 110

115 I claim:—

1. The herein described electric coupling consisting of a suitable stud; a metallic, snap-on contact member to fit said stud; and suitable elastic insulating material surrounding said contact member to assist the springiness of the same, and provided with a suitable opening through which connection with said contact member may be made.

120 2. The herein described electric coupling consisting of a suitable stud; a metallic contact member to fit said stud; and suitable elastic insulating material within which said member is embedded, said material being 125 130

provided with a blind opening through which connection with the said contact member may be made.

3. The herein described electric coupling 5 consisting of a suitable stud; a metallic, snap-on contact member to fit said stud; and suitable elastic insulating material within which said member is embedded, said material being provided with a blind opening 10 through which connection with the said contact member may be made.

4. The herein described electric coupling 15 consisting of a suitable stud; a metallic, snap-on contact member to fit said stud; and a rubber pad or cushion within which the 20 said member is embedded, said pad being provided with a blind opening through which connection may be made with said contact member.

20 5. The herein described electric coupling 25 consisting of a suitable stud, and insulating material surrounding the same; a metallic contact member to fit said stud; suitable insulating material surrounding said contact member and provided with a suitable opening 30 through which connection may be made with said contact member; and means on one of said insulations to resist the other, when the said stud makes contact with the 35 contact member, to produce a back pressure under the head of the said stud.

6. The herein described electric coupling 35 consisting of a suitable stud; two D-shaped conductors each having an indentation in the vertical line of the D; and a suitable 40 elastic insulating material within which said conductors are embedded in juxtaposition, said material being provided with an opening through which contact may be made with said conductors.

7. An electric connector comprising: two snap-on contact members; a flexible conductor connecting said contact members; and elastic insulating material within which each 45 of said contact members is embedded, the said material surrounding said contact members being provided at each contact member with a suitable opening through which connection may be made with the respective 50 members.

8. An electric connector comprising: two snap-on contact members; a flexible conductor connecting said contact members; and elastic insulating material surrounding said 55 flexible conductor and within which each of said contact members is embedded, the said material surrounding said contact members being provided at each contact member with a suitable opening through which connection 60 may be made with the respective members.

9. An electric connector comprising: two

65 snap-on contact members; a flexible conductor connecting said contact members; and elastic insulating material surrounding said flexible conductor and within which each of 70 said contact members is embedded, the said material surrounding said contact members being provided at each contact member with a blind opening through which connection may be made with the respective members. 70

10. An electric connector comprising: two snap-on contact members; a flexible conductor, and a cord or the like, connecting said contact members; and elastic material surrounding said flexible conductor and the 75 cord or the like, and within which each of said contact members is embedded, the said material surrounding said contact members being provided at each contact member with a suitable opening through which connection 80 may be made with the respective members.

11. The combination with an electric coupling member consisting of a metallic, snap-on contact member, and elastic insulating 85 material surrounding the same and provided with a suitable opening, of a suitable stud to receive said contact member, and means on one of said co-acting members adapted to operate with the other to afford a high insulation, water tight joint. 90

12. The combination with an electric coupling member consisting of a metallic contact member, and suitable elastic insulating material surrounding said contact member and provided with a suitable opening, of a 95 suitable stud adapted to enter said opening to make contact with said contact member, insulating material surrounding said stud, and means on said insulating material to resist the said elastic insulating material of 100 the contact member when the said stud makes contact with the contact member.

13. The combination with an electric coupling member consisting of a metallic contact member, and suitable elastic insulating 105 material surrounding said contact member and provided with a suitable opening, of a suitable stud adapted to enter said opening to make contact with said contact member, and insulating material surrounding said 110 stud, said insulating material being provided with a ridge to resist the said elastic insulating material surrounding said contact member.

Signed at Leicester, in the county of 115 Leicester, England, this 4th day of February A. D. 1910.

ISAAC HARDY PARSONS.
